UNITED STATES PATENT OFFICE

SCOTT O. MARTIN AND ELMER H. BRIDENBAUGH, OF DENVER, COLORADO, ASSIGNEES,
BY DIRECT AND MESNE ASSIGNMENTS, OF ONE-HALF TO A. M. NASSIF, OF DENVER,
COLORADO, AND ONE-HALF TO SAID SCOTT O. MARTIN

DITCHING PLOW

Application filed May 19, 1928. Serial No. 278,948.

This invention relates to improvements in ditching plows of the type shown and described in United States Letters Patent No. 1,648,236, granted November 8, 1927.

It is the object of this invention to produce a ditching plow that shall be so constructed that it can be readily adjusted to vary the inclination of the ditch and which shall also be provided with means for holding it in level position regardless of the inclination of the land on which it is used.

This invention, briefly described, consists of a beam having attached thereto two mold boards which extend outwardly at an angle from each other and have their front ends connected so as to form a point. A shoe is pivotally connected with the front end of this assembly and adjustable about a pivot for the purpose of determining the angle that the blades make with the horizon. A pair of wheels is adjustably secured to the assembly and is independently adjustable so as to make it possible to maintain the ditching plow in level position when making a ditch on a side hill.

Having thus briefly described the invention we will now proceed to describe the same in detail and for this purpose reference will be had to the accompanying drawings in which the preferred embodiment thereof has been illustrated and in which:

Figure 1 is a top plan view of the ditching plow;

Fig. 2 is a side elevation of the same;

Fig. 3 is an end view of the plow showing the same to a somewhat larger scale than in Figures 1 and 2 and showing it in position in the ground;

Fig. 4 is a section taken on line 4—4, Fig. 1;

Fig. 5 is a section taken on line 5—5, Fig. 4, and shows the means for locking the adjusting wheels in position;

Fig. 6 is a section taken on line 6—6, Fig. 4;

Fig. 7 is a section taken on line 7—7, Fig. 3, and

Fig. 8 is a section taken on line 8—8, Fig. 1.

In the drawings numeral 1 designates a beam which is preferably made from steel and is shaped somewhat like an ordinary plow beam. The rear end of this beam is curved

at 2 and has a downwardly and forwardly extending portion 3 whose lower end 4 is inclined forwardly at a somewhat greater angle than the part indicated by numeral 3. End 4 is provided with an opening for the reception of the bolt 5 which serves as a pivot for the point or toe 6. Secured to the rear end of the toe is a shoe 7 whose rear end is provided with an upwardly extending part 8 that is perforated for the reception of a pivot 9. The pivot 9 serves to connect the part 8 with the heel 10. Two adjusting braces 11 have their lower ends secured to the heel 10 and are connected at their upper ends and provided with a rack 12. Secured to the part 3 of the beam is a support 13 which is held in place by means of rivets 14. The front end of the blades or mold boards 15 are fastened to this support by means of bolts 16. Support 13 is provided with a sharp rib 17 which projects forwardly in front of the front ends of the mold boards 15 in the manner shown in Figure 2. A transverse brace member 18 extends between the blades a short distance back of their point of connection and this transverse brace has its ends connected with the blades so that it is rigidly attached to them. Brace members 19 have their rear ends attached to the transverse brace 18 and have their front ends attached to the plate 20. The front ends of braces 19 are also connected with the beam 1 by means of rivets 21 in the manner shown in Figure 4. It is now apparent that by means of the triangular structure comprising brace members 18 and 19 to which the blades 15 are connected, that the latter are rigidly secured to the beam so as to be held in a predetermined relation with it. Extending between the blades and attached to the latter at their rearmost ends is a transverse brace member 22. This brace member is secured to the blades by means of angle brackets 23 in the manner shown in Figure 3. The ends of brace bar 18 to which attention has been directed above, are secured to the blade braces 24 which are shown in Figure 3. A similar transverse brace 25 extends between the two blades and has its end secured to the braces 24 in the manner also shown in Figure 3.

105

Secured to the transverse brace members 18 and 22 are supporting brackets or jack straps 26. These straps have two sides which are bent at an angle to each other and have their vertices extending upwardly in the manner shown in Figure 2. Secured to the vertices of these brackets are bearings 27 in which is supported a shaft 28. Rotatably mounted on this shaft are three hand wheels 29, each of which has an elongated hub portion 30 which is provided at its end with gear teeth 31. These hand wheels are held in spaced relation by means of sleeves 32. For the purpose of holding the hand wheels against accidental rotation a locking device has been provided for each of the wheels. This locking device consists of a hook 33 that is pivotally secured to the angle 22 by means of a bolt 34. The end of this hook is provided with two spaced fingers 35 that embrace one of the spokes in the manner shown in Figures 4 and 5. Secured to the heel 10 are two angle irons 11 that extend upwardly in the manner shown most clearly in Figure 4 and have their upper ends secured to a rack member 12. This rack engages the pinion 31 carried by the center hand wheel. A roller 36 is pivotally attached to a bracket 37 that is supported on one of the jack straps 26. This roller 36 is provided with spaced flanges that embrace the rack 12 and holds it in adjusted position with respect to the pinion 31. By rotating the hand wheel 29, it is evident that the rack 12 can be moved upwardly or downwardly and held in adjusted position by means of the locking member 33. When rack member 12 is moved downwardly, the shoe 7 will be rotated about the axis of bolt 5 from the full line towards the dotted line position shown in Figure 2. By this means therefore it is possible to adjust the angular relationship between the shoe 7 and the blades 15 and beam 1. For the purpose of guiding the heel member 10, guides 38 have been provided. These guides consist of angle irons whose upper ends are secured to the transverse brace 18 and whose lower ends are attached to the inclined angles 39. The guides 38 occupy the position with respect to the angle iron 11 shown in Figure 6 from which figure it will be seen that angles 11 can move vertically but cannot move sidewise and by this means the shoe 7 will be held against sidewise movement.

For the purpose of holding the ditching plow in any desired transverse position with respect to the ground, wheels 40 have been provided. These wheels are secured to shafts 41 which, in turn, are mounted for rotation in bearings 42. These shafts are provided with collars 43 that keep them from moving longitudinally in the bearings. The bearings are fastened to an angle iron 44 by means of bolts 45 so as to produce a rigid connection between the wheels. A draw bar 46 has its rear end rigidly connected to the angle 44

by means of a clamping bracket 47 shown most clearly in Figure 6. The front end of this draw bar is provided with an opening 48 for the reception of a hook 49 which is formed in the end of the bolt 50. This bolt is secured to the beam 1 in the manner shown in Figure 4. It will be observed from Figure 6 that the draw bar extends through the space between the angle irons 11 which therefore serve as guides that prevent the wheel assembly from moving transversely while permitting it to move vertically. For the purpose of adjusting the vertical position of the wheels, angle irons 51 have been pivotally connected to the wheel assembly by means of pins 52. The upper ends of these angles are provided with racks 53 that are held in operative relation with pinions 31 by means of rollers 36 in the manner shown in Fig. 7. By rotating either one of the hand wheels 29 that are connected with the racks 53, the end of the wheel assembly to which this rack is connected can be raised and lowered. As the hand wheels are movable independent of each other, it is evident that each end of the wheel assembly can be independently adjusted. When the wheel assembly has been adjusted to the position desired, the hand wheels can be locked by means of the locking member 33, which has already been described. Wheels 40 are located between the blades 15 near their rear ends and engage the inclined surface of the ditch in the manner shown in Figure 3. The rims of wheels 40 have been made concave and provided with a sharp inner edge 54 which cuts into the soft soil and serves to prevent sidewise movement. A seat 55 is secured to the outer end of a spring 56 which in turn rests on the transverse brace 22 and is secured to the latter by means of a pin 57. The front end of the spring is provided with an eyelet 58 through which the bent bar 59 extends in the manner shown in Figure 3. The ends of bar 59 are connected with the brace members 39. When the operator sits in the seat, the tendency of the spring 56 to rotate about the supporting member 22 is resisted by the bar 59 in the manner quite apparent.

For the purpose of attaching a team of horses to the ditching plow or for connecting it with a tractor, a tongue 60 has been provided. The rear end of this tongue is provided with two members 61 that form a tongue adjusting head. Members 61 are secured to the tongue by means of rivets or bolts 62 and are provided at their rear ends with three spaced openings 63. A bolt 64 extends through one of the openings 63 and through an opening in the beam 1 and serves as a means for attaching the rear end of the tongue to the beam. The front end of beam 1 is attached to spaced vertical plates 65 that embrace the tongue 60 and have their lower ends connected by means of a bolt 66. A rack

67 is pivotally attached to the upper surface of the tongue by means of a bolt 68 and this rack is provided with a rib on its convex surface which cooperates with a groove in a 5 roller 70 and the concave surface of this rack is provided with teeth 71 that are adapted to be engaged by the teeth on pinion 72. Pinion 72 is secured to a shaft 73 which also carries a worm gear 74. A worm 75 is rotatably mounted in a bracket 76 and has attached to it a shaft 77 by means of which it can be rotated. This shaft extends rearwardly to a position adjacent the seat where it terminates in a handle 78. The driver, by engaging 10 the handle 78, and rotating the rod 77, can rotate the worm gear 74 and thereby adjust the position of the beam with respect to the tongue. Secured to the tongue directly in front of the adjusting rack 67 are two 15 hitch bars 79, one of which is located on each side of the tongue. The upper ends of these bars are pivoted at 80 to the upper end of a bracket 81 in the manner shown in Figure 8. These bars are provided with several spaced 20 holes 82 by means of which adjustments can be made. The lower ends of the hitch bars are connected to the bolt 64 by means of rods 83 whose front ends are secured to the hitch bars by means of bolts 84. The whiffle-trees or the traction member by means of 25 which the plow is connected to a tractor is also secured to the lower ends of hitch bar 79 and has been indicated by numeral 85. By adjusting the vertical position of the 30 hitch bars the point of the draft attachment can be varied vertically. By means of the adjustment just described and by means of the rack and pin mechanism which changes the angle between the beam 1 and the tongue 35 40, it is possible to effect several important adjustments which enable the operator to get the best and most satisfactory operation. The point of attachment of the tongue to the beams which has previously been described 45 also assists in obtaining the desired adjustment.

By means of the mechanism described above the angular relationship of the shoe 7 and point 6 can be altered which makes it possible to determine the extent of the downward pull exerted by the plow when in operation. The adjustment of the wheels 40 makes it possible to maintain the plow in a horizontal or level position when cutting a 45 ditch transversely along an inclined field as the wheels can be independently adjusted to conform to the inclination.

It is apparent that by adjusting the angle between the plane of the cutting edges of the mold boards 15 and the horizon that the inclination of the sides of the ditch can be varied. The more nearly horizontal the cutting edges are, the shallower the ditches will be and conversely the greater the angle between the cutting edges and the horizontal,

the steeper the sides of the ditch will be. The bottom of the point 6 can be made of considerable width so as to make the bottom of the ditch flat in the manner shown in Fig. 3.

By means of a ditching plow of the type 75 above described, a ditching operation can be very satisfactorily performed for the reason that this ditching plow is provided with so many different adjustments that almost any desired result can be quickly obtained.

The point 6 is readily detachable and can therefore be replaced if broken. It is also possible to substitute a point of a specifically different shape. The point shown in Fig. 3 has a flat bottom and consequently makes a 80 ditch with a flat bottom. If a ditch having a V-shaped bottom is desired a correspondingly shaped point is used.

Having described the invention what we claim as new is:

1. A ditching plow comprising a beam having its rear end downwardly and forwardly inclined, a pair of cutter blades attached at their front ends to the downwardly and forwardly extending part of the beam, 90 a transverse brace member connecting the blades at a point to the rear of the beam, diagonal braces extending from points near the ends of the transverse brace member to the beam, a shaft having a wheel secured to each end thereof, said wheels and shaft being located between the blades near their rear ends, a draw bar connecting the shaft to the beam, a pair of guides cooperating with the draw bar and means for independently adjusting each end of the shaft separately.

2. A ditching plow comprising a beam having its rear end downwardly and forwardly inclined, a pair of cutter blades attached at their front ends to the downwardly and forwardly extending part of the beam, 105 a transverse brace member connecting the blades at a point to the rear of the beam, diagonal braces extending from points near the ends of the transverse brace member to the beam, a shaft having a wheel secured to each end thereof, said wheels and shaft being located between the blades near their rear ends, a draw bar connecting the shaft to the beam, 110 a vertical guide bar located on each side of the draw bar and means for adjusting each end of the shaft independently with respect to the plane of the cutting edges of the blades.

3. A ditching plow comprising a beam having its rear end curved downwardly and forwardly, a pair of cutter blades having their front ends connected with the beam, said blades diverging from each other in a rearward direction, a plurality of transverse braces extending between the cutting blades, 125 brackets secured to two of said transverse braces, a shaft supported on said brackets, a hand wheel supported on the shaft, a point pivotally connected with the beam and cutter blade assembly, a shoe extending rearwardly 130

- from the point, a vertical brace bar secured to the rear end of the shoe, a rack secured to the upper end of the brace bar, a pinion connected with the hand wheel, said pinion cooperating with the rack whereby the shoe and point may be adjusted when the hand wheel is rotated and means for latching the hand wheel in adjusted position.
4. A ditching plow comprising a beam having its rear end curved downwardly and forwardly, a pair of cutter blades having their front ends connected with the beam, said blades diverging from each other in a rearward direction, a plurality of transverse braces extending between the cutter blades, brackets secured to two of said transverse braces, a shaft supported on said brackets, two hand wheels supported by the shaft, a shaft assembly located between the blades near their rear ends, a draw bar secured at one end to the shaft assembly and at the other end with the beam and blade assembly, a vertical guide associated with the draw bar, a supporting bar secured to each end of the shaft assembly, the upper ends of said bars having racks attached to them and pinions carried by the hand wheels for cooperating with the racks whereby the ends of the shaft assembly may be adjusted vertically when the hand wheels are rotated.
5. A ditching plow comprising a beam having rigidly secured to one end thereof, a pair of rearwardly divergent cutter blades, a tongue having one end connected with the beam near its rear end, means for making connection between the tongue and the front end of the beam, said last named means comprising a rack pivotally attached to the tongue, a plate attached to each side of the beam, said plates enclosing the tongue, and means for rotating the pinion and for holding it in any given position, whereby the angular relation between the tongue and the beam can be altered at will and retained in altered position.
6. A ditching plow having a beam, a pair of cutter blades rigidly connected with the beam, said blades being rearwardly divergent, the cutting edges of the blades lying in a plane, a point connected with the blades near their front ends, said point being movable about a pivot whose axis lies parallel with the plane of the cutting edges, a shoe extending rearwardly from the point, a rack attached at its lower end to the rear end of the shoe, a pinion connected with the blades, said pinion being operatively associated with the rack whereby when the pinion is rotated the shoe and point will be moved about their pivot, and latching means for holding the pinion against accidental rotation.

In testimony whereof we affix our signatures.

SCOTT O. MARTIN.
ELMER H. BRIDENBAUGH.
